Attorneys.

UNITED STATES PATENT OFFICE.

JOHN L. McMILLAN, OF SYRACUSE, NEW YORK.

LOOSE-LEAF BINDER.

Application filed December 9, 1925. Serial No. 74,352.

This invention pertains to loose leaf binders of the type in which the leaves or sheets bound are carried upon links or cross bars which bridge the binder back and are engaged at their ends by pintles of slidable pintle-carrying bars, movable longitudinally in casings carried by the cover boards at or about the lines of the hinges or flexible joints connecting the boards with the back member.

The invention consists in novel means for locking and releasing the pintle bars or slides to prevent or permit, as desired, insertion or removal of a sheet or sheets and in a novel construction of the housing for said slides.

One of several embodiments of the invention is illustrated in the accompanying drawings, in which:

Figure 1 is a perspective view of the complete binder with leaves held therein;

Fig. 2, a partly sectional view of the locking mechanism on a much larger scale;

Fig. 3, a perspective view of one end of the housing or casing of one of the pintle-bearing slides, showing the cylindrical portions which receive the pintles and the lock shell or body, and other details of the housing;

Fig. 4, a perspective view of one of the leaf-carrying links;

Fig. 5, a fragmentary perspective view of one of the pintle slides, showing one pintle, the lock shell or body, its radial guiding rib or wing, and the rotatable lock cylinder, fitting closely within the shell and permanently connected with the pintle slide by a swivel joint, as better shown in Fig. 2;

Fig. 6, a perspective view showing one form of permanent hinge connection between the back member and the cover boards.

The binder shown comprises the usual curved back or member 1, and two cover boards 2 and 3 hinged to or flexibly connected therewith in any usual or known way.

Firmly secured to and preferably built into either or each of the cover boards, preferably both, is a metallic casing or housing 4 formed of a sheet metal blank bent or folded longitudinally near its midwidth to produce a cylindrical guideway 4^a for pintles 5 of a bar or slide 6 and a rectangular guideway 7 for the body of said pintle bar or slide 6, and for a radial rib 8 of the lock shell or casing 9.

One wall of the guideway 7 is conveniently formed, as shown in Fig. 3, by bending the

metal sheet or blank at a right angle, and this wall, together with two further right angle bends of the blank, produce an inwardly projecting U-shaped rib 10, the intermediate wall of which makes contact with the other half of the blank. This rib or corrugation 10 acts as a spacing member for the parallel halves of the folded blank, casing or housing 4, and greatly stiffens and strengthens the same against bending or buckling transversely.

Beyond the rib, the parallel free plates of the housing 4, separated and held properly spaced apart by rib 10, afford a seating between them for the inner edge of a base 3^a of binder's board or like foundation or body of the cover board. This is firmly secured in place by rivets, spurs, inturned edges of the housing, or in any other known and convenient way, preferably effected before the leather, canvas or other covering material 3^b is applied to the cover boards or to the back member. The covering material 3^b is usually turned inward upon the board 3^a, mitered at the outer corners thereof, and covered by a facing sheet 3^c of paper, which extends over practically the entire inner surface of board 3^a, as seen in Fig. 6.

As shown in the drawing, one end of the cylindrical folded edge of the housing 4 is enlarged to form an outer or enclosing shell 11, to receive the lock shell or casing 9, which is of such diameter as to produce a close but sliding and turning fit therein. This outer shell is provided with a longitudinal slot or opening 12, terminating at its inner end in a lateral extension 13, as seen in Fig. 3. The purpose of this opening is to receive a stud or pin 14, carried by and projecting radially from the rotatable cylinder 15 of the lock, which is of the well known Corbin or Yale type, having radially movable stems or tumblers 16 registering with similar stems or tumblers 17 seated in the lock shell or casing and urged inward by springs 18. A flat key which may be grooved or corrugated to fit a corresponding keyway in the lock cylinder has one edge fashioned to press outward the pins or tumblers 16 and thereby to force back the stems or tumblers 17, so that the abutting ends of the two sets shall be in line with the meeting line of the cylinder 15 and its shell or casing 9, as seen in Fig. 2. When the key thus sets the stems or tumblers no one of them crosses the line

or extends from cylinder into casing or from casing into cylinder, hence the cylinder is made free to rotate through turning of the key. As soon as the cylinder begins to turn 5 each set of tumblers is prevented from moving longitudinally, and the inner ends of the stems or tumblers 16 resting in notches or depressions in the edge of the key preclude its withdrawal until the lock cylinder 10 is returned to locking position. When so returned the key may be withdrawn, forcing all the tumblers radially outward and thereby compressing the springs 18, which, on withdrawal of the key, expand, moving the 15 tumblers inward, and causing the outer tumblers 17 to stand across the meeting line of cylinder and shell, thereby precluding any rotation of the cylinder and consequently any unlocking of the lock.

20 When the lock is carried to its normal position within its enclosing shell 11, the pintle slide 6 is moved to position to pass its pintles 5 through the eyes or perforations 19 of links 20, the perforated ends of which 25 enter through openings 21 formed in the tubular inner edge 4^a of each housing 4 to a point where their eyes or perforations are in alinement with the pintles. The pintles are advisably pointed at their free ends to 30 facilitate the entrance into the eyes, and they are advisably of a length slightly greater than the width of the openings 21, so that they may bridge the openings and extend slightly beyond them, so that their 35 forward ends may get a bearing beneath or within the tubular wall of the housing.

As seen in Fig. 1, the pintle slide 6 is provided with a serrated or milled button or thumb piece 22, lying outside the housing 4 but having a connecting stem passing 40 through an elongated opening 23 in the housing, by means of which button the slide may be moved longitudinally to cause the 45 pintles to engage or release the links 20, as desired, the lock being first unlocked to permit such movement.

When the lock and slide are in their normal locking position, the stud or pin 14 extending through a transverse or circumferential slot 24 in its shell, stands in the lateral extension 13 of opening 12 of the outer shell or casing 11, in which position it securely holds the lock and the connected pintle slide against longitudinal movement, thus 50 preventing withdrawal of the pintles from the links 20, which withdrawal is a condition precedent to release of a link, and consequently to insertion or removal of a sheet into or from the binder.

55 Slot or opening 12 is of a length just sufficient to permit the requisite travel of the pintle slide to effect passage of the pintles through the eyes of the links to and from link retaining position.

60 With the parts constructed and arranged

as described and shown it is necessary merely to insert the key into the keyway of cylinder 15, turn the key and cylinder a distance sufficient to move stud 14 out of lateral extension 13 and into alinement with the main slot or opening 12, and by pulling rearwardly upon the key or pressing button or thumb piece 22 in pintle withdrawing direction, to move the lock and slide outward and thereby withdraw the pintles from and thus release the links 13 at one end. When the necessary insertion, removal, or transposition is completed the slide and lock are pressed or moved back to normal position and locked by turning the key in a direction 70 opposite to that in which it was turned to effect unlocking. The opposite ends of the links may be similarly secured, or they may be hinged in any way to the proximate cover board. In practice I find it preferable to 75 provide like attaching and locking means for both ends of the links.

While I prefer a lock of the Corbin or Yale type because of its compactness and security, any other type of lock that is suitable may obviously be employed.

By permanently connecting the lock and the pintle slide all danger of loss of the lock is avoided, the stud 14 and slot 12 precluding complete withdrawal of the lock, and consequently, any removal of the pintle slide.

For brevity, and particularly to shorten the claims, a binder such as above described may be designated as a loose leaf binder of 100 the link and pintle type.

It is also to be understood that though the words "slide" and "housing" are used in the claims, these parts may be duplicated in practice and preferably will be, and the 105 claims are to be read with this understanding.

What is claimed is:—

1. In a loose leaf binder of the link and pintle type, a housing carried by the binder; 110 a pintle slide longitudinally movable within the housing; and a lock carried by the slide and serving when locked, to hold the slide against longitudinal movement.

2. In a loose leaf binder of the link and pintle type; a housing carried by the binder; 115 a pintle slide longitudinally movable within the housing; and a lock carried by the slide and having a rotatable member provided with a stud adapted to be carried into and out of a retaining seat in the housing by rotation of said member in opposite directions.

3. In a loose leaf binder of the link and pintle type, a housing carried by the binder and provided with a longitudinal slot having a lateral extension; a pintle slide longitudinally movable within the housing; and a lock having a swivel connection with the 125 slide and provided with a rotatable tumbler 130

barrel having a stud to enter and traverse the slot, and to enter the lateral extension of the slot to prevent longitudinal movement of the slide.

- 5 4. In a loose leaf binder of the link and pinte type, a housing carried by the binder and provided with a longitudinal slot having a lateral extension; a pinte slide longitudinally movable within the housing; a 10 lock having a swivel connection with the slide and provided with a rotatable tumbler barrel having a stud to enter and traverse the slot and to enter its lateral extension to prevent longitudinal movement of the slide; 15 and key-controllable tumblers carried by the tumbler barrel and the lock shell and serving, when the key is withdrawn, to prevent rotation of the tumbler barrel.

5. A loose leaf binder, comprising a cover; 20 a housing carried by the cover; sheet-carrying links having perforate ends extending into said housing; a pinte-carrying slide within the housing; and a lock having a swivel connection with the slide and adapted 25 to make locking engagement with the housing, the lock and slide being capable of longitudinal movement to carry the pintles of the slide into and out of the eyes of the sheet-carrying links.

30 6. A loose leaf binder, comprising a cover; a housing carried by the cover and provided with a slot having a lateral extension; sheet-carrying links having perforate ends extending into said housing; a pinte-carrying slide 35 within the housing; a lock having a swivel connection with the slide, the lock and slide being capable of longitudinal movement to carry the pintles of the slide into and out of the eyes of the sheet-carrying links; and 40 a rotatable member forming a part of the lock and provided with a stud to enter and traverse the slot in the housing and to enter and withdraw from the lateral extension of the slot, to prevent or to permit longitudinal 45 movement of the lock and slide.

7. In a loose leaf binder of the character described, a housing formed of a sheet metal blank bent or folded near its midwidth into tubular or cylindrical form, said tubular 50 portion being enlarged at one end to receive a lock barrel, the portions of the blank at either side of such tubular fold being brought parallel with each other and spaced

apart a distance sufficient to receive between them a radial extension of said lock barrel 55 and one edge of a cover-board.

8. In a loose leaf binder of the character described, a housing formed of a sheet metal blank bent or folded near its midwidth into tubular or cylindrical form, the portions of 60 the blank at either side of such tubular fold being brought parallel with each other and spaced apart a distance sufficient to receive between them a cover-board and a radial portion of 65 a lock barrel, one leaf of the folded blank being provided with a longitudinal rib or corrugation projecting toward the opposite leaf of the blank, serving as a stiffening member to prevent buckling of the blank, and acting as a spacing member to 70 maintain the two leaves of the blank at proper distance apart.

9. In a loose leaf binder of the character described, a sheet metal housing folded at or near its midwidth into tubular or cylindrical form, the portions of the blank at either side of such tubular fold being brought parallel with each other and spaced apart a distance sufficient to receive between them a cover-board and a radial portion of 75 the lock barrel; and a lock having a barrel adapted to fit snugly within one end of the tubular fold of the housing, and having a radial portion to extend between the parallel leaves of the housing.

10. In a loose leaf binder of the character described, a housing formed of a sheet metal blank bent or folded near its midwidth into tubular or cylindrical form, the portions of 80 the blank at either side of such tubular fold being brought into parallel planes and spaced apart a distance sufficient to receive between them a portion of a lock casing, said tubular portion of the housing having a longitudinal slot with a lateral extension; a lock 85 having a shell of cylindrical form to fit snugly within the tubular portion of the housing and provided with a radial extension to fit between the leaves of the housing, 90 said lock provided with a rotatable barrel having a radial extension projecting through its shell or casing and extending into the slot in the housing.

In testimony whereof I have signed my name to this specification.

JOHN L. McMILLAN.
